Primary Examiner — Deanna L Pratt(74) *Attorney, Agent, or Firm* — Cantor Colburn LLP(57) **CLAIM**

I claim, the ornamental design for a display screen portion with graphical user interface, as shown and described.

DESCRIPTION

The FIGURE is a front view of a display screen portion with graphical user interface showing my new design.

The broken lines illustrating portions of the display screen portion with graphical user interface are for environmental purposes only and form no part of the claimed design.

1 Claim, 1 Drawing Sheet
